UNITED STATES PATENT OFFICE

GEORGE CASHAN MURPHY, OF LOUISVILLE, KENTUCKY, ASSIGNOR OF ONE-HALF TO
FRANK H. POSCHINGER, OF LOUISVILLE, KENTUCKY

COLLAPSIBLE ELEVATOR-CAB GATE

Application filed February 4, 1930. Serial No. 425,782.

This invention relates to certain improvements in collapsible folding gates, used for the protection of entrance ways to elevator cabs, such gates being provided upon the cab 5 to close the opening in front of same, while the elevator car or cab is in operation.

Various other types of collapsible gates have been used for some time, but certain objections have been raised to these gates, which 10 are not common to my improved gate. My construction provides that the gate, when started to open, will begin collapsing at one extreme end, same being accomplished by certain preferred mechanism hereinafter specifically described and shown in the drawings, causing my gate to collapse only behind the panel at the front of the cab and not in front of the opening, consequently at no time does my gate collapse or change its position 15 across the front of the opening.

Another object of my invention is the construction of an efficient yet simple collapsible closure for an opening, which will not catch the wearing apparel or hands or legs of the 20 operator or passenger, while in the act of closing or moving the gate from in front of the opening of the car or cab.

Another object of my invention is to provide simple central bracing means for the 25 bars of the gate or closure.

With the foregoing and other objects in view, my invention comprises certain novel constructions, combinations and arrangements of parts as will be hereinafter fully 30 described, illustrated in the accompanying drawings, and more particularly pointed out in the appended claims.

In the drawings:

Figure 1 is an elevated front view of a 35 mechanism constructed in accordance with the present invention, while

Figure 2 is an end view of the same, showing the overhead track in section.

Figure 3 is a sectional view taken on line 40 3—3, Figure 1, and looking in the direction of the arrows.

Figure 4 is an enlarged perspective view of one of the cam-track devices.

Figure 5 is an enlarged sectional view taken

on line 5—5, Figure 1, and looking in the direction of the arrows.

Figure 6 is an enlarged fragmentary, vertical sectional view of two of the tubular bars, showing their connecting means in a folded 55 position.

Figure 7 is an enlarged fragmentary sectional view of the mechanism showing the manner of collapsing or folding the bars together, as they approach and line up by the 60 cam-track devices.

Figure 8 is an enlarged sectional view taken on line 8—8, Figure 1.

Referring to the drawings by numerals, 1 designates the car or cab of the usual type of 65 an elevator, with a panel 2 on the front thereof.

The preferred form of my gate comprises a plurality of tubular bars 3. Each bar 3 has a pin 4 (Fig. 2) set in its lower end, and this 70 pin 4 travels in a track 5 on the floor 2a of the car or cab 1. On the upper end of each bar 3 is an L-shape casting 6. A grooved roller 7 is suitably mounted on the upper end of casting 6; this roller 7 travels on the overhead 75 track 8. A roller 9 is suitably mounted on casting 6 near its base, and travels against the lower edge of track 8 (Fig. 2). The track 8 is suspended by members 10 from the brackets 11 mounted on the top of the cab 1.

Each two contiguous vertical bars 3 are connected by a connecting device 12. The connecting device 12 comprises a single link 13 pivotally mounted upon rivet or pin 14, and link 13 extends at its outer end between the pair of links 15 (Fig. 5); the inner ends of links 15 are pivotally mounted on pin or rivet 16. The outer overlapping ends of links 13 and 15 are pivotally connected by a pin or bolt 17 on which is journalled roller 18. The links 13 and 15 extend into the tubular bars 3 through elongated slots 19. The bottom 20 of these slots are a considerable distance below the pins 16, so that when the connecting devices are in their normal position, the roller carrying ends will be below the pins 14 and 16. Also the lower edges of the links will be resting on the lower ends of the slots 19, whereby the links can not pivot further downwardly, and by reason of 100

the "sagging" down of the links, the connecting devices will normally be locked to prevent the bars from being folded together. It is to be noted that the outer pin 14 is on the outer bar whereas all of the other pins on which the links are mounted are designated by 16. It is also to be noted that the connecting devices 12 are placed near the bottom and the top of the bars 3 (Fig. 1).

As the object of my invention is to keep the bars from folding until they approach the panel 2, to accomplish the folding action, I place two cam-track devices 21 at the top and bottom of the panel 2. Each cam-track device comprises a horizontal plate 22 having apertures 23 for allowing the plate to be secured by screws, or like means, not shown, to the panel portion 2 of the cab. A grooved track 24 is fastened through the medium of ears 25 to the plate 22. This track 24 has a downwardly extending end 26 with outwardly flared lips 27, constituting a cam. The rollers 18 enter the track between lips 27 passing upward in the cam end 26 and thence along the horizontal portion of the track. As the roller 18 enters the track (Fig. 7) the "knee" or joint of the connecting device 12 is "broken," causing the links to fold together in a compact manner, as shown in Figures 1 and 7, behind or parallel with the panel 2. The bars will close very closely together, as particularly illustrated in Figure 6.

A bumper device 28 is secured on the floor 2a in the path of movement of the gate, so that the innermost bar hits against the bumper and causes the folded bars to stop within the space of the panel 2.

The gate is braced near the center by pivotally mounting at 29 a plurality of cross bracing bars 30. While the inner end of each bar 30 is pivotally mounted on the tubular bars 3, at 29, their outer ends are slidably mounted on the bars, by reason of being connected to pin 31 (Fig. 8). This pin extends through slot 32 formed in the bar. On pin 31 is a roller 33 that travels in said slot 32. On pin 31 is placed a washer 34 which prevents the roller from being removed in one direction from slot 32 whereas the bar 30 keeps the roller in from the opposite direction. Therefore, it will be seen that bars 30 suitably brace the gate without interfering with the folding or collapsing action of the bars 3.

It is to be noted that the primary bars 3 are connected by hinged or pivoted connecting devices that of their own weight, automatically move to a locked position, for holding the contiguous bars spaced, when the connecting devices have passed beyond the outer mouth of the cam-track devices, but when these connecting devices come in contact with the cam-track devices, they automatically fold together for permitting snug collapsing of the primary bars.

In the following claims, I use the term "support" to broadly designate a car or cab body or any part thereof.

While I have described the preferred embodiment of my invention and illustrated the same in the accompanying drawings, certain minor changes or alternations may appear to one skilled in the art to which this invention relates, during the extensive manufacture of the same, and I, therefore, reserve the right to make such alterations or changes as shall fairly fall within the scope of the appended claims.

What I claim is:

1. In a mechanism of the class described, the combination with a support, of a gate comprising a plurality of vertical bars on said support, movable connecting devices between said bars, cam-track devices on said support, and said connecting devices provided with means engaging said cam-track devices for operating the same and closing said vertical bars together.

2. In a mechanism of the class described, the combination with a support, of a plurality of cam-track devices on said support, a collapsible gate on said support and adapted to be closed parallel with said cam-track devices, said cam-track devices and gate provided with means for closing the gate together, and said gate provided with means for locking it in a closed position beyond said cam-track devices.

3. In a mechanism of the class described, the combination of a cab provided with an overhead track, a plurality of vertical bars, a casting on the upper end of each bar, a pair of rollers carried by said casting and travelling on the upper and lower edge of said overhead track, movable connecting devices connecting said bars, and said cab provided with means for moving said movable connecting devices and causing the bars to fold or close together when the gate is manually operated from an open position.

4. In a mechanism of the class described, the combination of a cab provided with an overhead track, a plurality of vertical bars, L-shape castings having their lower ends on said vertical bars, spaced rollers extending out from each L-shape casting and engaging opposite edges of said overhead track, movable connecting devices on said bars and normally locking them in an open position, and said cab provided with means for moving said connecting devices and causing the bars to fold or collapse together when the gate is manually operated from an open position.

5. In a mechanism of the class described, the combination with a support, of a gate carried by said support and comprising a plurality of tubular bars, means holding said bars on said support, each bar provided with a slot, a connecting device pivotally mounted

in the slots of two contiguous bars, said connecting device comprising links, said links being held in a locked position on the lower ends of said slots, and means on said support 5 for breaking the joint of said connecting devices and thereby causing the bars to close together thereby opening the gate.

6. In a mechanism of the class described, the combination with a support, of a gate 10 carried by said support and said gate comprising a plurality of vertical tubular bars, said bars provided with elongated slots, each two contiguous bars connected by a link connecting device, the links of each connecting device 15 pivotally mounted in the elongated slots of the bars and provided at their overlapping outer ends with a roller, and said support provided with means for engaging said roller and causing the same to move upward for 20 breaking the joint of the links and causing the bars to collapse or fold together.

7. In a mechanism of the class described, the combination with a support, of a sliding gate comprising vertical bars on said support, 25 said bars connected by connecting devices, said connecting devices each comprising overlapping links, a roller carried on the overlapping portions of the links of each connecting device, and cam means on said support 30 and engaging said rollers for causing the same to be moved in a vertical plane for collapsing the bars.

8. A collapsible elevator gate, comprising bars, link devices connecting said bars, and 35 means co-operating with the central portion only of said link devices for moving them in a vertical plane for causing the bars to fold together.

9. In a mechanism of the class described, 40 the combination with a support, of an upper and a lower cam-track device on said support, each cam-track device comprising a plate, a grooved track secured to said plate, said grooved track provided with a cam end 45 and with outwardly flared lips, a collapsible gate on said support and including connecting devices provided with rollers, and said rollers adapted to pass between said outwardly flared lips and into said end of said track and into 50 the grooved track for closing or collapsing said gate bars contiguous to said cam-track devices as the gate is moved to open position.

10. In a mechanism of the class described, 55 the combination with a cab provided with a panel, of an upper and a lower cam-track device within said panel, each cam-track device provided with a grooved track having a cam-like end, a plurality of vertical bars 60 slidably mounted on said cab, connecting devices for said bars and adapted to normally lock the bars in spaced open condition, and each connecting device provided with means adapted to engage a cam-like end and enter 65 the grooved track for causing the bars to col-

lapse together as the gate is moved to open position.

11. In a mechanism of the class described, the combination with a cab provided with a panel, of cam-track devices secured on said panel, each cam-track device comprising a horizontal plate, a track provided with ears against said plate, said track provided with a cam-like end, and a collapsible gate provided 70 with means engaging said cam-like ends of said tracks and travelling on said tracks, whereby the gate bars are collapsed parallel with the panel as the gate is moved to open position.

12. In a collapsible gate, the combination 80 of a plurality of vertical bars, connecting devices for each two contiguous bars, each connecting device comprising a single link extending into one bar and a pair of links 85 extending into another bar, said single link extending at its outer end between the outer ends of said pair of links, a pin extending through the overlapping ends of said links, a roller on said pin near its outer end, said links adapted to "sag" down at their connected 90 ends for locking the bars apart, and means for engaging said rollers and causing same to move upwardly for breaking the joints of the links and causing the bars to close together when manually operated. 95

In testimony whereof I hereunto affix my signature.

GEORGE CASHAN MURPHY.
